UNITED STATES PATENT OFFICE.

RUDOLPH PEDEN, OF HARRISON, ARKANSAS.

PENCIL HOLDER AND SHARPENER.

1,085,473.

Specification of Letters Patent.

Patented Jan. 27, 1914.

Application filed May 13, 1913. Serial No. 787,405.

To all whom it may concern:

Be it known that I, RUDOLPH PEDEN, citizen of the United States, residing at Harrison, in the county of Boone and State of 5 Arkansas, have invented certain new and useful Improvements in Pencil Holders and Sharpeners, of which the following is a specification.

This invention relates to combined pencil 10 holders and sharpeners, and has for one of its objects to provide a simply constructed device adapted to be supported upon a pencil and assist in holding the latter from displacement in the pocket, and at the same 15 time provide an effectual device whereby the pencil may be sharpened.

With these and other objects in view the invention consists in certain novel features of construction as hereinafter shown and 20 described and then specifically pointed out in the claims, and in the drawings illustrative of the preferred embodiment of the invention, Figure 1 is an elevation of the improved device applied to a pencil. Fig. 2 25 is a section on the line 2—2 of Fig. 1. Fig. 3 is an elevation with the lower portion in section on the line 3—3 of Fig. 1. Fig. 4 is a detached perspective view of the cutting blade. Fig. 5 is a perspective detail illustrating a modification in the construction 30 of the body and the cutting blade. Fig. 6 is a perspective view of a modified construction of the cutting blade.

Corresponding and like parts are referred 35 to in the following description and indicated in all the views of the drawings by the same reference characters.

The improved device comprises a stock or body 10 having curved wings or arms 11 to 40 partially embrace the pencil represented at 12. The body 10 is formed with an upwardly directed extension 13 enlarged at 14 preferably in the form of a ball. The body 10 is also provided with a downwardly ex- 45 tended trough-like portion 15, the latter preferably extending obliquely to the longitudinal plane of the body as shown in Fig. 3. The downwardly directed portion 15 is provided with an opening 16 and with dove- 50 tailed guideways 17—18 to receive a cutting blade 19, the latter having dove-tailed edges to engage in the dove-tailed portions 17—18. The blade 19 is formed with a concaved cutting edge 20 in its upper edge. The

dove-tailed guideway 18 is deeper than the 55 guideway 17 so that the cutting edge 20 is spaced for a considerable distance from the upper edge of the opening 16 so that the cutting edge 20 of the blade extends for a distance inwardly of the inner face of the 60 oblique portion of the extension 15, as illustrated in Fig. 3, to provide a passage for the shavings as they are severed from the pencil as hereafter explained. The wings 11 65 coact with the extension 13 to support the pencil 12 spaced a sufficient distance from the knife-edge 20 to prevent the latter from engaging the pencil except when the latter is to be sharpened. By this means when the improved device is located upon a pencil 70 at the farthest point from the sharpened end with the extension 13 directed toward the sharpened end of the pencil, the extension 13 forms a clip to bear over the upper edge of the pocket and thus secure the pencil 75 in position relative to the pocket and prevent its accidental displacement.

When the device is to be employed as a pencil sharpener it is detached from the pencil and the end to be sharpened drawn 80 repeatedly over the cutting edge 20 of the blade and the pencil turned slowly until the desired "point" is produced.

The improved device is simple in construction, can be inexpensively manufactured, and plated or otherwise ornamented. 85

The blade 19 will preferably be slightly tapered from end to end and the guideways 17—18 correspondingly tapered, so that the blade is held by a slight wedge-like pressure 90 to prevent its accidental displacement.

In Fig. 4 the blade 19 is shown with a curved cutting edge, but the cutting edge may be straight, as shown in Fig. 6. In Figs. 1—2—3 the blade 19 is shown constructed separately from the frame 10 and inserted in dovetailed grooves, while in Fig. 5 the blade is shown integral with the frame 10. Either form of the construction may be employed without departing from 95 the principle of the invention or sacrificing any of its advantages.

Having thus described the invention, what is claimed as new is:

1. A combined pencil holder and sharpener comprising a body having lateral wings to engage a pencil and with a trough-like extension extending obliquely to the longi- 105

tudinal plane of the body and a cutting blade transversely of the extension and extending at its cutting edge into the same.

2. A combined pencil holder and sharpener comprising a body having a trough-like extension extending obliquely to the longitudinal plane of the body, and a cutting blade transversely of the extension and extending at its cutting edge into the same.

10 3. A combined pencil holder and sharpener comprising a body having a trough-like extension extending obliquely to the longitudinal plane of the body, said extension having an opening, and a cutting blade supported upon said extension transversely of said opening and projecting at its cutting edge into the extension.

15 4. A combined pencil holder and sharpener comprising a body having a trough-like extension directed obliquely to the longi-

tudinal plane of the body, and a cutting blade transversely of the extension and extending at its cutting edge into the same.

5. A combined pencil holder and sharpener comprising a body having a trough-like extension extending obliquely to the longitudinal plane of the body, said extension having an opening with its terminals dovetailed, and a cutting blade having dovetailed edges engaging the terminals of the opening and extending transversely of the same and projecting at its cutting edge into the extension.

In testimony whereof I affix my signature in presence of two witnesses.

RUDOLPH PEDEN. [L. s.]
